Patented June 4, 1912.

UNITED STATES PATENT OFFICE.

ELMER J. MYERS, OF MARTINSBURG, PENNSYLVANIA, ASSIGNOR OF ONE-HALF TO
CHARLES F. BROWN, OF HOLLIDAYSBURG, PENNSYLVANIA.

VALVE-GEAR.

1,028,592.

Specification of Letters Patent.

Patented June 4, 1912.

Application filed March 2, 1911. Serial No. 611,895.

To all whom it may concern:

Be it known that I, ELMER J. MYERS, a citizen of the United States, residing at Martinsburg, in the county of Blair and 5 State of Pennsylvania, have invented certain new and useful Improvements in Valve-Gear, of which the following is a specification.

The present invention relates to certain 10 new and useful improvements in valve gear for steam engines, and has for its object to provide a valve gear which is comparatively simple and inexpensive in its construction, which is positive and reliable in operation, 15 and in which all of the parts are readily accessible for oiling or repairing.

A further object of the invention is the provision of a valve gear which embodies novel features of construction whereby the 20 vibratory movement of the pitman is utilized to control the admission and exhaust of steam from the cylinder, and which admits of the engine being readily reversed and the amplitude of movement of the valve 25 in the valve chest regulated as required.

With these and many other objects in view which will more readily appear as the nature of the invention is better understood, the same consists in the novel construction, 30 combination, and arrangements of the parts hereinafter more fully described, illustrated, and claimed.

The essential features of the invention involved in carrying out the objects above 35 specified are necessarily susceptible to a wide range of structural modification without departing from the scope of the invention, but a preferred embodiment thereof is shown in the accompanying drawings, in 40 which:—

Figure 1 is a top plan view of a stationary engine having the improved valve gear applied thereto. Fig. 2 is a side elevation of the same. Fig. 3 is a detail view showing a modification in which the valve rod moves horizontally instead of vertically, as 45 shown in Figs. 1 and 2.

Corresponding and like parts are referred to in the following description and indicated in all the views of the drawings by the same reference characters.

The improved valve gear may be applied to an engine of any suitable type, although 50 in the present instance it is shown, for the purpose of illustration, as applied to a sta-

tionary engine in which the cylinder is horizontally disposed. This engine may be of any approved construction, and includes a bed 10 upon one end of which the cylinder 11 is mounted, the said cylinder being provided with the usual piston which is arranged to reciprocate back and forth therein and is connected to a piston rod 12. The free end of this piston rod 12 is secured to a cross head 13 which slides upon the guides 60 14 and is connected by a pitman 15 to a crank 16 at one end of a shaft 17, the said shaft being journaled in the bearings 18 and provided with a fly wheel 19. The admission of steam to the cylinder and exhaust 65 of steam therefrom is controlled by means of a suitable reciprocating valve operating within a valve chest 20, the said valve being connected to a valve stem 21 which projects through the steam chest and terminates in 70 a head 22 having a slot 23 formed therein.

The pitman 15 is provided with a longitudinally disposed rib 24, the said rib being shown in the present instance as constituted by one of the flanges of an angle iron 25 80 which is rigidly secured to the pitman in some suitable manner as by means of the fastening members 26. A bifurcated block or slide 27 engages the rib 24, and this block is shown as provided with a rearwardly projecting stem 28 which is loosely received within an opening in the free end of a lever 30. A nut 31 is applied to the extremity of the stem 28 to hold the lever 30 in engagement therewith, and the 85 said lever is formed with a centrally disposed offset portion 30^a whereby the two ends of the lever are caused to be disposed in spaced and parallel planes. One end of the lever is, as previously described, pivotally connected to the block 27, while the opposite end of the lever is pivotally connected at 32 to a bracket 33 projecting from the bed of the engine. With this construction, it will be apparent that when the engine is 90 in operation the rib 24 will slide back and forth in the block 27 and will also cause the lever 30 to be oscillated as the pitman is vibrated up and down.

A slotted arm 34 projects from the offset 105 portion 30^a of the lever 30 and is spaced from and parallel to the pivot end of the said lever. This slotted arm 34 loosely receives a pivot pin 35 carried by one end of a main lever 36, the said main lever be- 110

ing pivoted at a point between the ends thereof upon a pin 37 which is slidably mounted upon a slotted supporting plate 38. In the present instance this supporting plate is shown as having one end thereof secured to a bracket 39 which projects upwardly from the bed 10. The opposite end of the main lever is provided with a pin 40 which is slidably received within the slot 23 of the head 22 at the upper end of the valve stem. The main lever 36 is designed to be moved back and forth longitudinally so that the pin 35 can be caused to assume a position upon either side of the pivot 32 of the lever 30 or in alinement with the said pivot. When the pin 35 is in alinement with the said pivot 32, the up and down movement of the lever 30 will not cause any movement of the main lever 36, while when the pin 35 is upon one side of the pivot 32, the movement of the lever 30 will cause a swinging movement of the main lever 36 about the pin 37 at the middle portion thereof. The ends of the main lever 36 will thus vibrate back and forth, and this movement will be imparted to the valve stem 21 through the head 22 at the upper end thereof. The amplitude of movement would, however, depend upon the amount the pin 35 had been shifted laterally to either side of the pivot 32, and the direction of movement could be reversed by shifting the pin 35 from one side of the pivot point 32 to the opposite side. It will thus be apparent that the engine could be readily reversed by suitably shifting the central pivot point or pin 37 of the main lever 36 to move the lever longitudinally, and that the amplitude of movement imparted to the valve stem could also be regulated so as to cause the admission of a large or small amount of steam to the cylinder at each stroke, as may be desired.

A slight modification is shown in Fig. 3, in which the valve chest 41 is horizontally disposed instead of being vertically disposed as in the previous instance, and the valve stem 42 must accordingly be moved horizontally instead of vertically. In order to accomplish this result a bell crank lever 43 is utilized, one end of the bell crank lever being connected to the valve stem 42, while the opposite end of the bell crank lever is connected to the end of the main lever 36. It will thus be obvious that as the rear end of the said lever 36 is moved up and down, the bell crank lever will operate to produce a back and forth movement of the valve stem 42. The manner of imparting movement to the said main lever 36 from the pitman of the engine is identical with that which has been previously described.

Having thus described the invention, what I claim as new and desire to secure by Letters Patent, is:—

65 1. A valve gear for steam engines, in-

cluding a lever mounted to receive motion from the pitman, an arm projecting from the lever, a second lever having one end thereof connected to the before mentioned arm by an adjustable pivot which can be shifted to either side of the pivot of the first mentioned lever, and an operative connection between the second lever and the steam valve of the engine. 70

2. A valve gear for steam engines, including a guide rib upon the pitman of the engine, a lever, a block carried by the lever and slidably engaging the said guide rib whereby an oscillating movement is imparted to the lever, an arm projecting from the lever, a second lever, a pivot pin on the lever, said second lever having one end thereof connected to the arm by said pivot which can be shifted to either side of the pivot of the first mentioned lever, and an operative connection between the second lever and the steam valve of the engine. 75

3. A valve gear for steam engines, including a lever mounted to receive motion from the pitman of the engine, an arm projecting from the lever, a second lever capable of lateral adjustment, a pivot pin mounted thereon, said second lever having one end thereof connected to the said arm by the said pivot pin which can be shifted 90 to either side of the pivot of the first mentioned lever, a support upon which the pivot of the second mentioned lever is adjustably mounted to admit of the said lever being shifted back and forth to reverse the 95 movement thereof and regulate the amplitude of movement, and an operative connection between the second lever and the steam valve of the engine. 100

4. A valve gear for steam engines, including a lever mounted to receive motion from the pitman, an arm projecting from the lever, a second lever capable of lateral adjustment, a pivot pin mounted thereon, said second lever having one end thereof connected to the arm by said pivot pin which can be shifted to either side of the pivot of the first mentioned lever by a longitudinal movement of the second mentioned lever, a support upon which the pivot of the second mentioned lever is slidably mounted to admit of the said lever being moved to regulate the amplitude of movement thereof or reverse the direction of movement, and a head applied to the valve 110 stem and having a sliding connection with the opposite end of the second lever. 115

5. A valve gear for steam engines, including a lever mounted to receive motion from the pitman, a slotted arm projecting from the lever, a second lever capable of lateral adjustment, a pivot pin mounted thereon, said second lever connected to the arm by a pivot member which is adjustable 125 within the slot and can be shifted to either 130

side of the pivot of the first mentioned lever by a longitudinal movement of the second mentioned lever, a slotted support adjustably receiving the pivot of the second mentioned lever whereby the said second mentioned lever can be moved back and forth to regulate the amplitude of movement thereof or reverse the direction of movement thereof, a slotted head applied 10 to the valve stem, and a pin upon the opposite end of the second lever adjustably engaged by the said slotted head.

6. A valve gear for steam engines, including a longitudinal rib upon the pitman 15 of the engine, a lever, a block carried by the free end of the lever and engaging the rib upon the pitman whereby a vibratory motion is imparted to the lever, a slotted arm projecting from the lever, a second lever 20 capable of lateral adjustment, a pivot pin mounted thereon, said second lever having

one end thereof connected to the arm by said pivot pin which is slidable within the slot so as to be shifted to either side of the pivot of the first mentioned lever, a slotted support upon which the pivot of the second mentioned lever is adjustably mounted to admit of the said second mentioned lever being shifted back and forth to regulate the amplitude of movement thereof or reverse the direction of movement thereof, a slotted head applied to the valve stem, and a pin at the free end of the second lever loosely engaged by the said slotted head.

25 In testimony whereof I hereunto affix my signature in the presence of two witnesses.

ELMER J. MYERS.
